Attorney

UNITED STATES PATENT OFFICE.

GEORGE A. STRAWSER, OF LIVERPOOL, PENNSYLVANIA, ASSIGNOR OF ONE-HALF TO
DANIEL W. GOODLING, OF RICHLFIELD, PENNSYLVANIA.

ATTACHMENT FOR SPARK PLUGS.

Application filed September 14, 1922. Serial No. 588,185.

To all whom it may concern:

Be it known that I, GEORGE A. STRAWSER, a citizen of the United States, residing at Liverpool, in the county of Perry, State of Pennsylvania, have invented certain new and useful Improvements in Attachments for Spark Plugs; and I do hereby declare the following to be a full, clear, and exact description of the invention, such as will enable others skilled in the art to which it appertains to make and use the same.

This invention relates to new and useful improvements in spark plugs for explosive engines, and particularly electrodes therefor.

One object of the invention is to provide an electrode which will prevent collection of carbon on the plug, thereby improving the efficiency of the sparking of the plug.

Another object is to provide an electrode which will effectively drain any fuel which might enter the lower end of the plug, and hold the fuel below the sparking edge of the electrode.

Other objects and advantages will be apparent from the following description when taken in connection with the accompanying drawing.

In the drawing:

Figure 1 is an elevation of the lower portion of a spark plug, partly in section, showing the position of the electrode.

Figure 2 is a similar view showing the electrode in section, and slightly enlarged.

Figure 3 is a horizontal sectional view of the plug on the line 3-3 of Figure 1, showing the electrode in top plan.

Referring particularly to the accompanying drawing, 10 represents the metallic shell of the spark plug, and 11 represents the central electrode. Disposed within the lower end of the shell 10 is a horizontally disposed disk 12, having a central opening 13 through which the electrode 11 is disposed, this latter electrode being so arranged that it is spaced from the wall of the opening. The surrounding wall of the opening 13 extends downwardly from the upper face of the disk to a point close to the lower face, where it curves abruptly toward the center of the

opening, to form the circular knife edge 14, which forms the other sparking point of the plug.

Radiating from the upper edge of the opening 13, to points close to the peripheral edge of the disk, are the grooves 15, the walls of which converge in a direction away from the center opening of the disk. In the lower face of the disk, surrounding the opening 13, and comparatively close thereto, is a small circular groove 16, which is adapted to draw, by capillary action, any oil or gasoline which enters the shell 10. It will be noted that the groove 16 is disposed at such a distance away from the opening 13 as to hold the fuel out of the path of the exploding gases, with the result that clogging or collecting of carbon, on the knife edge 14, is effectively prevented. The oil remains in the groove 16 during the compression stroke of the piston of the engine, but is driven out upon the exhaust.

The knife edge 14 insures that the firing will take place outside of the shell of the spark plug, and within the combustion chamber of the engine.

It will be noted that the radiating grooves 15 have their bottoms inclined downwardly and inwardly from the upper outer edge of the disk to the wall of the opening 13, thus more readily permitting the shell to be cleaned, by suction, when the engine exhausts.

What is claimed is:

1. A sparking electrode comprising a disk having a central opening with a sparking knife edge at one end of the opening, radiating channels, and capillary means for preventing accumulation of fuel on said knife edge.

2. A sparking electrode comprising a disk having a central electrode receiving opening the lower end of which is formed with an inwardly extending knife edge, radiating downwardly and inwardly inclined channels, and a channel in the lower face of the disk surrounding the central opening.

3. A sparking electrode comprising a disk having a central opening formed with an inwardly directed knife edge at one end, down-

wardly and inwardly inclined radiating V-shaped channels the walls of which converge toward the outer periphery and upper face of the disk, and a circular groove surrounding the lower end of the central opening for drawing oil, by capillary action from the knife edge.

In testimony whereof, I affix my signature, in the presence of two witnesses.

GEORGE A. STRAWSER.

Witnesses:

CLARENCE BARNER,
A. M. BARNER.
